UNITED STATES PATENT OFFICE.

HARRY E. EURICH, OF OTSEGO, MICHIGAN.

BEATER ENGINE.

Application filed August 8, 1924. Serial No. 730,853.

To all whom it may concern:

Be it known that I, HARRY E. EURICH, a citizen of the United States, residing at Otsego, county of Allegan, State of Michigan, have invented certain new and useful Improvements in Beater Engines, of which the following is a specification.

This invention relates to improvements in beater engines.

10 The main object of this invention is to provide an improved beater engine having a continuous discharge.

A further object is to provide an improved beater engine which is of large capacity.

15 Objects pertaining to details and economies of construction and operation of my improvements will definitely appear from the detailed description to follow.

I accomplish the objects of my invention 20 by the devices and means described in the following specification. The invention is clearly defined and pointed out in the claims.

A structure which is a preferred embodiment of my invention is clearly illustrated 25 in the accompanying drawing forming a part of this application, in which:

Fig. I is a plan view of a beater engine embodying the features of my invention, parts being shown mainly in conventional 30 form for convenience in illustration.

Fig. II is a fragmentary view partially in vertical section on a line corresponding to line 2-2 of Fig. I looking in the direction of the arrows.

35 In the drawing similar reference numerals refer to similar parts in both views.

Referring to the drawing, the embodiment 40 of my invention illustrated comprises the elongated tank 1 having a central midfeather 2 at one side of which the beater roll 3 and the coacting backfall 4 are disposed. These parts are shown conventional- 45 ly as the structure thereof is well known in the art.

45 At the ends of the midfeather the tank is provided with discharge openings 5 which deliver to the stock chest or to a spout not here illustrated. The foraminated drums 6 are disposed vertically to embrace these dis- 50 charge openings, the drums being supported and driven by the vertically disposed shafts 7, the lower ends of which are carried by the stirrup-like hangers 8 and the upper ends of the shafts being supported by the 55 arms 9.

On the upper end of the shaft is a beveled

gear 10 driven from the gear 11 on the jack shaft 12 connected to a suitable source of power as by the belt 13. The lower end of the drum is embraced by an annular guard 60 14 which prevents the stock flowing directly under the drum. Within the drum is a cylindrical weir 15 open at the top and bottom, the weir surrounding the discharge opening 5. The weir is provided with a collar 16 at 65 its upper end secured to the shaft by means of the set screw 17 so that the weir rotates with the shaft. The weir is surrounded by the guard 18.

This weir is of proper height to determine 70 the flow of strained stock and also relieves the screen of excessive pressure, that is, if there were no head within the screen a large amount of water would be drawn off from the beater and the screen would be subjected 75 to quite heavy pressures. The height of the weir is gauged relative to the normal height of the beater. The weir is also adapted as a drain valve, that is, it may be elevated as shown by dotted lines in Fig. II for draining 80 the tank.

To clean the screen I provide doctor blades 19 which are mounted upon the midfeather to coact with the screens and I also provide the spray pipes 20 which are arranged at 85 the rear of the doctor blades to discharge against the screens, either steam or water, as may be desired, so that clogging the screens is effectively prevented.

My improved beater engine is of large ca- 90 pacity, the stock being continuously drawn off or discharged, and this without clogging. I am aware that beater engines having continuous discharges have been provided but my experience is that these are not efficient 95 in that they rapidly become clogged or the discharges are of restricted capacity. Experience has demonstrated that in my improved beater engine this difficulty is not present.

Having thus described my invention what I claim as new and desire to secure by Letters Patent is:

1. The combination in a beater engine comprising a tank provided with a midfeather, a beater roll and a coacting backfall, of a foraminated drum open at the bottom disposed vertically at one end of said midfeather, there being a discharge opening in the bottom of the tank within said drum, a supporting and driving shaft for said drum, a cylindrical weir surrounding said dis-

charge opening and adjustably mounted on said shaft, a doctor blade mounted on said midfeather to coact with said drum, and a spray pipe disposed behind said doctor blade and directed against said drum.

2. The combination in a beater engine comprising a tank provided with a midfeather, a beater roll and a coacting backfall, of a foraminated drum open at the bottom disposed vertically at one end of said midfeather, there being a discharge opening in the bottom of the tank within said drum, a supporting and driving shaft for said drum, a cylindrical weir surrounding said discharge opening and adjustably mounted on said shaft, and a doctor blade mounted on said midfeather to coact with said drum.
3. The combination in a beater engine comprising a tank provided with a midfeather, a beater roll and a coacting backfall, of a foraminated drum open at the bottom disposed vertically at one end of said midfeather, there being a discharge opening in the bottom of the tank within said drum, a supporting and driving shaft for said drum, and a cylindrical weir surrounding said discharge opening and adjustably mounted on said shaft.
4. The combination in a beater engine comprising a tank provided with a midfeather, a beater roll and a coacting backfall, of a foraminated drum open at the bottom disposed vertically at one end of said midfeather, there being a discharge opening in the bottom of the tank within said drum, a supporting and driving shaft for said drum, an annular guard mounted on the bottom of said tank to embrace the bottom of said drum, and a cylindrical weir surrounding said discharge opening and adjustably mounted on said shaft.
5. The combination in a beater engine including a tank having a discharge opening in the bottom thereof, of a cylindrical screen open at the bottom and disposed vertically in said tank to embrace said discharge opening thereof, means for rotating said screen, a weir disposed within said screen to surround said discharge opening, a doctor

blade coacting with said screen, and a spray pipe disposed to discharge against said screen at the rear of said doctor blade.

6. The combination in a beater engine including a tank having a discharge opening in the bottom thereof, of a cylindrical screen open at the bottom and disposed vertically in said tank to embrace said discharge opening thereof, means for rotating said screen, a weir disposed within said screen to surround said discharge opening, and a doctor blade coacting with said screen.

7. The combination in a beater engine including a tank having a discharge opening in the bottom thereof, of a cylindrical screen open at the bottom and disposed vertically in said tank to embrace said discharge opening thereof, means for rotating said screen, a weir disposed within said screen to surround said discharge opening, and a spray pipe disposed to discharge against said screen.

8. The combination in a beater engine including a tank having a discharge opening in the bottom thereof, of a cylindrical screen open at the bottom and disposed vertically in said tank to embrace said discharge opening thereof, means for rotating said screen, and a weir disposed within said screen to surround said discharge opening.

9. The combination in a beater engine including a tank having a discharge opening of a cylindrical screen open at the bottom disposed vertically in said tank to embrace said discharge opening, means for driving said screen, and a weir disposed within said screen to enclose said discharge opening, said weir being vertically adjustable and constituting a drain valve for the tank.

10. The combination in a beater engine including a tank having a discharge opening, of a cylindrical screen open at the bottom disposed vertically in said tank to embrace said discharge opening, and means for driving said screen.

In witness whereof I have hereunto set my hand.

HARRY E. EURICH. [L. S.]
